UNITED STATES PATENT OFFICE.

WILLIAM L. MORROW, OF STOCKTON, CALIFORNIA.

GAS-ENGINE.

No. 869,253.

Specification of Letters Patent.

Patented Oct. 26, 1907.

Application filed October 31, 1906. Serial No. 341,372.

To all whom it may concern:

Be it known that I, WILLIAM L. MORROW, a citizen of the United States, and a resident of Stockton, in the county of San Joaquin, State of California, have invented certain new and useful Improvements in Gas-Engines; and I do declare the following to be a full, clear, and exact description of the same, such as will enable others skilled in the art to which it appertains to make and use the same, reference being had to the accompanying drawings, and the characters of reference marked thereon, which form a part of this application.

This invention relates to improvements in gas engines, and particularly to that type known as double two cycle engine, my object being to produce an engine having a separate compression chamber whereby the engine will be under continuous compression; also one having an all open port mechanism with pistons forming the only valve gates; also a compact, simple and inexpensive engine.

20 This object I accomplish by means of the main cylinder provided with a compression chamber arranged at the side thereof, means for conveying the compressed mixture from said compression chamber to said cylinder; and by such other, and further construction as will appear by a perusal of the following specifications and claims.

In the drawings similar characters of reference indicate corresponding parts in the several views.

Figure 1 is a side elevation of the engine. Fig. 2 is a longitudinal section thereof enlarged. Fig. 3 is a vertical section of said engine on the line 3—3 of Fig. 2.

1 designates the main cylinder and 2—2 are two pistons arranged therein end to end and connected to a crank 3 on a shaft 4, said shaft being journaled through the center of said cylinder.

5 is a compression chamber arranged at the side of said cylinder 1 and in which are arranged pistons 6 end to end and connected to a crank 7 on the shaft 4 in such a manner that said pistons 6 will operate alternately to the pistons 2 for the purpose as will hereafter appear.

The crank 7 is of less length than the crank 3, so that the piston 6—6 have a shorter stroke than the piston 2—2, and the chamber 5 is of sufficient length so that a considerable space constantly occurs between the piston 6—6 and the ends of the cylinder, while the length of the cylinder 1 is such that the pistons 2—2 nearly reach the ends of the cylinder when in their upward positions.

Ports 8—8 extend obliquely between the cylinder end and the chamber 5, the oblique ports being constantly uncovered at the ends leading to the chamber 5, and are alternately uncovered at the ends leading into the cylinder at the alternate strokes of the pistons 2—2.

That is to say, when the pistons 6—6 are at one end of the stroke one of the ports 8 will be uncovered both at its chamber end and its cylinder end, while the other

port 8 will be uncovered at its chamber end but will be covered by one of the pistons 2 at its cylinder end, as shown in Fig. 2, the object of this arrangement to be hereafter described.

9—9 are the exhaust ports leading from the cylinder 1 and which open when the pistons 2 reach their inward position, about one-half inch ahead of the ports 8, thus allowing the exhaust to occur before the inrush of the mixture.

10—10 are the usual jump sparks.

11 are intake ports opening into the chamber 5 with check valves.

12—12 are baffle plates of the usual construction on the piston 2.

In practice the backward drive of one of the pistons 6 draws the mixture through one of the ports 11. The forward drive of said piston compresses this mixture near the outer end of the chamber 5, and since with the forward drive of said piston 6, the other piston 2 in the same end of the engine is driven backward, this opens one of the ports 8 and the mixture then passes into the cylinder 1 just a fraction behind the exhaust. The forward drive of the said piston 2 then compresses this mixture near the front of the machine where it is exploded, thus driving the engine. Thus I have produced an engine provided with a separate compression chamber whereby the mixture is doubly compressed by alternating pistons; also one which is under continuous compression; one having an all open port mechanism; and lastly one in which the several pistons are the only valve gates, thus doing away with intricate valve mechanisms and eccentrics. Another feature of the improved engine is its compactness and simplicity, there being practically but two parts each serving a double purpose viz.—the chambers 1 and 5 with their pistons each one forming an intake and compression mechanism.

This description embraces the present and preferred embodiment of my invention. However, such changes and modifications may be made within the scope of the appended claims without departing from the spirit of the invention.

Having thus described my invention, what I claim as new and desire to secure by Letters Patent is:—

1. In a gas engine of the class described, a cylinder, a cylindrical compression chamber, a shaft journaled through said cylinder and chamber and having oppositely disposed cranks respectively within the cylinder and the chamber, pistons operating in said chamber at opposite sides of said shaft and connected to the crank within the chamber, pistons operating in said cylinder at opposite sides of said shaft and connected to the crank within the cylinder, and passages between the cylinder and the chamber near the ends thereof and so arranged that the ends communicating with the chamber are constantly uncovered and the ends communicating with the cylinder are alternately covered and uncovered by the cylinder pistons.

2. In a gas engine of the class described, a cylinder, a cylindrical compression chamber, a shaft journaled through said cylinder and chamber and having oppositely disposed cranks respectively within the cylinder and the chamber, 5 pistons operating in said chamber at opposite sides of said shaft and connected to the crank within the chamber, pistons operating in said cylinder at opposite sides of said shaft and connected to the crank within the cylinder, and passages between the cylinder and the chamber near the 10 ends thereof and so arranged that the ends communicating with the chamber are constantly uncovered and the ends communicating with the cylinder are alternately covered and uncovered by the cylinder pistons, intake ports leading into the chamber near its ends and provided with check valves, exhaust ports leading from said cylinder, 15 and spark devices connected into said cylinder outside of the paths of the pistons therein.

In testimony whereof I affix my signature in presence of two witnesses.

WILLIAM L. MORROW.
